UNITED STATES PATENT OFFICE.

JOSHUA CLARIDGE, OF CHICAGO, ILLINOIS, ASSIGNOR TO PRO-TEX LABORATORIES, INC., OF CHICAGO, ILLINOIS, A CORPORATION OF ILLINOIS.

MEANS OF FIRE AND BURGLAR PROTECTION.

Application filed February 19, 1923. Serial No. 619,792.

To all whom it may concern:

Be it known that I, JOSHUA CLARIDGE, a citizen of the United States, and a resident of the city of Chicago, in the county of Cook and State of Illinois, have invented certain new and useful Improvements in a Means of Fire and Burglar Protection; and I do hereby declare that the following is a full, clear, and exact description of the same, reference 5 being had to the accompanying drawings, and to the numerals of reference marked thereon, which form a part of this specification.

This invention relates to means of fire and 15 burglar protection for use in connection with bank vaults, stores, warehouses and other places.

It has been suggested to prevent theft 20 from vaults or the like by employing poison gas which is liberated whenever the safe door was tampered with.

One of the principal objects of the invention is to provide improved means for liberating poison gas within a vault or the like.

25 Another object of the invention is to provide means set in operation by heat for releasing the poison gas.

A further object of the invention is to provide means for preventing the burning of 30 the contents of the vault as the result of the heat-operated release means.

Other and further important objects of this invention will be apparent from the disclosures in the specification and the accompanying drawings.

The invention (in preferred forms) is illustrated in the drawings and hereinafter more fully described.

On the drawings:

35 Figure 1 is a perspective view of one corner of a vault fitted with the present improvements.

Figure 2 is a section on the line 2—2 of Figure 1.

40 Figure 3 is a view similar to Figure 1 showing a modified form of the invention.

Figure 4 is a top plan view of the fluid container shown in Figure 1.

45 Figure 5 is a section on the line 5—5 of Figure 4.

Figure 6 is an elevation of the inside of a vault door fitted with a further form of the present improvements.

50 Figure 7 is a sectional view of the fluid container shown in Figure 6.

Figure 8 is a bottom plan view of the same with the casing in section.

As shown on the drawings:

In the form of construction shown in Figures 1 and 2, a series of radiating fuse strips 10 of combustible material are laid along the walls 11, floor 12 and ceiling 13 of the vault or the like to be protected.

These strips are connected to a bomb 14 adapted to contain a suitable gas or volatile liquid for repelling either fire or burglars or both. The construction of the bomb is shown more particularly in Figures 4 and 5, from which it will be seen that the bomb is supported by a loop 15 of combustible material so that when the latter burns the bomb drops on the floor and breaks. The body of the bomb is preferably glass so as to fracture readily when released and dropped on the floor and is closed by a metal cap 16 crimped thereon.

The fuse strips should be so distributed that no space on walls, ceiling or floor is left between them which is large enough to enable a hole to be made at that place of sufficient size to enable a man to crawl through.

As the usual method of breaking into vaults is with an oxyacetylene torch, the cutting of a hole in any of the six sides of a vault will ignite one or more of the strips 10 of combustible material. Fire will run along such strips until the bomb is reached and released.

Instead of strips, combustible paint may be employed as indicated in Figure 3. In this case the walls 17 are given a coat 18 of combustible paint which is in turn preferably covered with a layer 19 of fireproof paint to minimize the danger of accidental ignition of the combustible paint. The bomb 29 is connected to the paint 18 by fuse strips 30.

For protecting the vault door the arrangement shown in Figure 6 may be employed. In this construction the door 20 has arranged thereon a central strip 21 and connecting side strips 22 of combustible material. The bomb 23, as shown, is arranged on the door and is connected to the central strip 21 by a strip 24. To enable the bomb to be released, if a part of the vault other than the door is broken through, the remaining parts of the vault are covered with strips or paint of combustible material and such strips or paint are connected to the strip 21 by a flexible fuse member 25. The member

25, being flexible, allows the vault door to be opened and closed as desired without interfering with the fire and burglar protection means.

5 The bomb 23 (Figures 7 and 8) comprises a rectangular casing within which are arranged four containers 27 of readily frangible material such as glass. These containers are filled with the volatile liquid 10 or liquids employed for repelling fire or burglars or both. Centrally arranged between these containers is a cartridge 28 of explosive material adapted to be set off by the fuse 24 connected thereto. The explosion 15 of this cartridge breaks the containers 27 and scatters the contents in the vault.

Various substances or compositions may be employed for the combustible strips, paint or the like by which the fluids are to 20 be released. They may be formed of strips of celluloid. On the other hand, if it is desired to apply the material as a paint, a solution of celluloid in amylacetate may be employed.

25 When celluloid burns large volumes of gas are liberated, chiefly carbon dioxide, nitrogen and steam, which will force any fireproof covering away and allow sparks and burning particles to fall upon the contents of the vault.

30 While in some cases it may be advantageous to create large quantities of a gas such as carbon dioxide with a view to smothering any fire in the contents of the vault, I prefer where practical to make use of mixtures adapted to burn without substantial generation of gas.

35 Such a mixture may be made by the use of aluminum powder mixed with some 40 oxygen containing material like barium chloride. The reaction in such a mixture would be as follows:

45 Alumina is one of the most infusible substances known and barium chloride does not melt until 960° C. and has a considerably higher boiling point. To aid in the application of the mixture it may be 50 worked up into a paste with a small amount of sodium silicate or water glass, just sufficient to make the particles adhere.

55 Although such a mixture will be ignited if an oxyacetylene torch is used to cut through the walls of the vault, it would not be ignited if one of the side walls was formed of brick or concrete and a hole was cut by a chisel or drill.

To enable the poison gas device to act 60 under these conditions, a suitable fulminating composition may be employed either incorporated in the inflammable mixture or placed at suitable points therealong to enable the inflammable mixture to be set 65 off.

The paint which is placed over the combustible strips or paint is preferably fire-proof so as to minimize the liability of fire.

For this purpose the paint may conveniently contain such materials as asbestos, 70 alkaline silicates, borax, ground fluorspar, glass and similar substances.

The fire extinguishing fluid is preferably 75 carbon tetrachloride, as this substance, having a boiling point of only 76° C., is readily volatilized. Further, it is a heavier gas than air so that by spraying the liquid into the air adjacent the top of the vault the vapor produced will settle downwards onto the burning matter.

80 Other substances may be employed such as carbonic acid under pressure or materials which, when mixed, generate carbonic acid such as sodium carbonate and sulphuric acid. I prefer, however, to employ a substance 85 such as carbon tetrachloride which is non-corrosive, may be held in liquid form without employing high pressure and which does not have to be mixed with another reagent to bring out its valuable properties 90 as a fire extinguishing medium.

95 The poison gas used is preferably not of a highly poisonous nature such as a hydrocyanic acid, but rather one tending to produce discomfort and inability to see the contents of the vault.

100 For this purpose a volatile liquid having vapors adapted to act upon the respiratory organs, such as anhydrous stannic chloride having a boiling point of 114° C. may be used. Similarly a lachrymatory product such as chloropicrin may be employed.

105 Further a substance adapted to produce dense fumes in air may be used to prevent the objects within the vault being seen.

110 Preferably a plurality of such volatile liquids or gases are employed each having a different effect.

I claim as my invention:

1. The combination with a bank vault of 110 a container for protecting fluid, means for releasing such fluid operable by heat and a train of combustible material leading to such means, such material consisting principally of substances adapted to burn without substantial generation of gas.

115 2. The combination with a bank vault of a container for protecting fluids, one adapted more particularly to repel fire and another more particularly to repel burglars and means for releasing such fluids operable by heat and combustible material extending over the sides of the vault and so distributed thereon that no space free of such material is left which is large enough to allow a hole 120 to be made at that place of sufficient size to enable a man to crawl through.

125 3. A protection device comprising a container for protecting fluid, means for releasing such fluid operable by heat, and a train 130

of combustible material leading to such means, such material consisting principally of substances adapted to burn without substantial generation of gas.

5. A protection device comprising a container for protecting fluid, means for releasing such fluid operable by heat, a train of combustible material leading to such means, and a covering of fireproof material over such train.

6. A protection device comprising a container for protecting fluid, means for releasing such fluid operable by heat, and a train of combustible material leading to such

means, said combustible material including 15 powdered aluminum, an oxygen containing substance and a binder.

6. A protection device comprising a container for fire extinguishing fluid, means for releasing such fluid operable by heat and a 20 train of combustible material leading to such means, said combustible material consisting principally of substances adapted to burn without substantial generation of gas.

In testimony whereof I have hereunto 25 subscribed my name.

JOSHUA CLARIDGE.
